UNITED STATES PATENT OFFICE

2,566,109

BOWLING BALL RETARDER

Robert I. Anderson, Grand Haven, Mich., assignor
to The Brunswick-Balke-Collender Company,
Chicago, Ill., a corporation of Delaware

Application August 31, 1946, Serial No. 694,226

17 Claims. (Cl. 273—47)

1

This invention relates to a safety ball stop for bowling alleys, and is arranged in the form of a rockable cradle having means such that when the ball enters the cradle the ball will be brought to a stop, or nearly so, and the cradle will swing to a position to gently release the ball into the storage section of the ball return rack, the cradle then being automatically returned into position to receive another ball.

In bowling ball retarders, as known prior to the present invention, injury has often occurred to bowlers by reason of a ball following a preceding ball, and the second ball striking the first ball with an impact to drive the first ball through the retarder mechanism. Also during bowling a bowler will frequently move the balls in the storage section when picking up or preparing to pick up the ball he is using. When this occurs some of the balls are rolled toward the retarding or stopping mechanism. The cradle safety ball stop in the present invention is so constructed that even though a ball in the storage section may be in contact with the cradle at the same time that a ball enters the cradle, no impact is imparted to said ball in the storage section until the ball in the cradle is released from the mechanism and the slope of the return track causes them to roll back in the storage section.

In the present invention it is also impossible for a following ball to enter the cradle when a preceding ball is in the cradle. The cradle safety ball stop of the present invention is so constructed as to prevent injury to the bowler and at the same time possesses maximum efficiency in the retarding of the ball and passing of the same through the cradle.

Among the objects of my invention are: to provide a novel and improved safety ball stop, to provide a safety ball stop in the form of a cradle preventing a strong impact to a ball or balls in the storage section; to provide a cradle safety ball stop which, when the ball is in the cradle, will prevent a following ball from striking the ball within the cradle; to provide a safety ball stop having improved construction to prevent injury to the bowler, and at the same time one that will be efficient, reliable and positive in operation; to provide a cradle safety ball stop having means to receive the impact of the ball and permit rotation of the ball within the cradle without danger of the ball climbing up over the impact end of the cradle; to provide a novel cradle and controlling cylinder for receiving the initial impact of the ball, permitting the ball to then move into the storage section, and return the

2

cradle to initial position after the ball has passed therethrough; and to provide a cradle of the type referred to above, that is wide enough to retard the progress of a regular size bowling ball, but will permit a small diameter ball, such as a duck ball or the like, to freely pass right on through the cradle.

Other objects and advantages will become readily apparent from the following detailed description taken in connection with the accompanying drawings, wherein:

Fig. 1 is a fragmentary side elevation of the ball retarding end of a ball return rack in a bowling alley, and having a safety ball stop embodying my invention.

Fig. 2 is a side elevation of a safety ball stop embodying my invention, showing the ball stop frame in longitudinal vertical section, with the cradle in ball releasing position shown in solid lines, and in ball receiving position shown in dotted lines.

Fig. 3 is a vertical transverse section on the line 3—3 of Fig. 2.

Fig. 4 is a longitudinal vertical section on the line 4—4 of Fig. 3, but showing the cradle in ball receiving position.

Fig. 5 is a vertical transverse section on the line 5—5 of Fig. 4.

Fig. 6 is a transverse section on the line 6—6 of Fig. 4.

Fig. 7 is a transverse section on the line 7—7 of Fig. 4.

Fig. 8 is a side elevation of a modified form of my invention.

Fig. 9 is an end elevation looking toward the left hand side of Fig. 8.

While my invention further resides in the combination, construction and arrangement of parts illustrated in the accompanying drawings, I have shown therein for illustrative purposes only, a preferred embodiment and wish it understood that the same is susceptible of modification and change without departing from the spirit and scope of the appended claims.

In the form shown in the drawings, my invention comprises a stop frame 1 of generally triangular shape with the front edge vertical and the rear edge inclined upwardly and rearwardly. This frame comprises side plates 2 and 3, each of which at its upper end is formed with laterally extending right-angled flanges 4 secured by bolts, screws, rivets, or the like 5 to the under surface of the side spaced-apart members 6 and 7 of the rear end portion of the ball return track 8.

A short distance in front of the place where my

safety ball stop, is applied, the ball return rack is formed with the usual abrupt upwardly inclined portion 9, to absorb part of the momentum of the ball along the ball return rack. As soon as the ball has moved upwardly to the top of the incline 9 it will have sufficient momentum left to roll into the safety ball stop of the present invention and be retarded therein and pass therethrough to the storage section 10 where a number of the balls may be stored until picked up for use by the bowlers.

Each of the side plates 2 and 3 of the ball stop frame 1, at its upper edge, extends upwardly at 12 to receive the cross pin 13 around which cross pin is positioned a pair of flanged sleeves 14 and 15 upon which is rotatably mounted the hub 16 of the cradle 17. The pin 13 passes through the apertured upstanding projections 12 of the side plates and is held in such position, with the cradle rotatably mounted thereon, by the screws 18 and 19 which if desired may have washers positioned between the inner faces of their heads and the outer faces of the side walls 2 and 3. It is thus seen that the cradle 17 is swingably mounted on pin 13 in the upper portion of the space between the side walls 2 and 3. Cradle 17 extends a somewhat greater distance rearwardly of pin 13 than it does forwardly thereof. This rearwardly extending end as viewed in Fig. 4, when the cradle is in its initial ball receiving position, is formed with upstanding end portions 20 of the side plates 21 and 22 on which, at the rear upper extremities, is rotatably journaled a roller 23, which is preferably of rubber to resiliently receive the impact of the ball entering the cradle.

This roller 23 serves as to stop to receive the impact of the ball thereagainst. At the moment of impact the ball is revolving due to its rolling motion, and roller 23 being free to rotate about its shaft 24, allows the ball to revolve without tending to climb up over roller 23 and out of the cradle. If desired, a non-revolving stop may be provided in lieu of roller 23, in which case the surface of such stop would be of a material offering less friction so as to allow the surface of the ball to slide or slip with relation thereto. This will be visualized in Fig. 4 by assuming that the roller 23 is non-rotatable and of such slipping material.

Cradle 17 extends forwardly from its fulcrum pin 13 to provide the end portion 25, between the side plates of which is mounted the pin 26, upon which is mounted the roller 27 preferably formed of rubber or other resilient material.

Fixed by welding or otherwise in the upper portion of the space between the side plates 2 and 3 of stop frame 1, along the front edges thereof, is a channel member 28 to the upper end of which is fixed by spot welding or otherwise, a forwardly inclined metal plate or strip 29 so positioned as to form a stop for the forward roller 27 when the cradle is in its ball-receiving position as shown in Fig. 4. At this time the roller 27 is below the portion traversed by the lowest surface of the ball to permit the ball to enter the cradle and strike the roller 23 at the rear upper end of the cradle. As will be understood, the roller 23 at this time is standing a substantial distance above the ball return rack, and in fact is somewhat above the horizontal plane passing through the center of the ball when contacting roller 23.

Fixed to the rear curved end wall 30 of the cradle is a leather pad 31 to receive the slight impact from a ball in the storage section, should the same roll forwardly under force created by

the bowler's fingers when picking up another ball from said section. As will be noted in Fig. 4, this pad 31, which may be of leather or any other suitable cushioning material is positioned a substantial distance above the ball return rack when the cradle is in ball receiving position.

The side plates 2 and 3 of the stop frame 1 are at their inclined rear edges further secured and braced together by a channel member 32, spot welded or otherwise fixed thereto. The structural mounting of the roller 27 between the sides of the forwardly projecting ends 25 of the cradle will be more or less similar to the mounting of the cradle upon the stationary stop frame and need not be described in detail, except to state that any suitable supporting means that will permit rotation of the roller 27 may be used as will be understood in Fig. 7.

The means for absorbing the shock of the ball when it strikes the rear roller 23 and then slowly lowering the rear end of the cradle to permit the ball to roll into the storage section and to thereafter return the cradle to its initial position, will now be described. This means comprises generally a hydraulic cylinder 33 which has fixed in its lower end a fulcrum block 34, fulcrummed upon the pin 35, which pin in turn is mounted at its ends in the lower forward corners of the side walls 2 and 3 of the stop frame 1. Any suitable mounting may be employed as desired, it only being necessary that the hydraulic cylinder 33 rotate a small amount upon pin 35.

Slidably mounted within cylinder 33 is a piston 36 having a piston rod 37 which at its upper end is pivotally connected between side plates 21 and 22 of the cradle as shown in Fig. 4. This pivotal connection of the upper end of piston rod 37 with the cradle is shown in detail in Fig. 6 in which it will be seen that the upper tubular end of this connecting rod (which is closed by the threaded rod P) is passed through a central diametrical opening in the sleeve 38, and fixed therein by welding or other suitable securing means as indicated at 39. Extending inwardly from each end of the sleeve 38 is a flanged bushing 40 which at the inner end extends substantially to the outer surface of the piston rod 37.

Extending into each of the bushings 40 is a pin 41 threaded at 42 in complementary threads 43 formed in the hub portions 44 of plates 21 and 22. From this construction it is seen that the upper end of piston rod 37 has a pivotal movement with relation to the cradle 17, so that the piston rod and piston may move inwardly and outwardly with relation to the cylinder 33 as the cylinder swings about its fulcrum pin 35.

Piston rod 37 is slidably mounted through a central opening in the disk 45 secured in the cylinder 33 by screws or the like, 46. Disk 45 in fact constitutes a head for the upper end of the cylinder. The lower end of piston rod 37 is fixed in any desired manner within a hollow hub 47 fixed to the piston 36. The lower face of piston 36 is formed with a depression 48 having communication with the hollow interior of the piston rod.

The piston rod and piston hub 47 are each formed on diametrically opposite sides with openings forming passageways 50 and 51. Seated in a seat in the upper end of the depression 48 is a ball valve 52 which is held from falling out of the depression 48 by a spider 53 extending across the lower end of this depression. The rod P is threaded at its upper end T to enable longitudinal adjustment to cause its reduced lower

end 54 to hold ball 52 a selective small distance away from its port, so that when the cradle is rocked rearwardly by the impact of a bowling ball against roller 23 the oil or other fluid in cylinder 33 will slowly pass through the space between the ball and its seat to control such rearward swinging of the cradle to the desired degree. This degree will be controlled by longitudinal adjustment of rod P which construction in effect provides an adjustable hydraulic snub or retarding means.

During the rearward swinging of the cradle, it will be understood that the ball valve 52 is pressed against the end 54 of rod P to prevent more than the desired amount of liquid from passing upwardly through passageway 49. Mounted below the piston 36, and at its ends engaging the bottom face of the piston and the upper face of the bottom piston closing block 34 is a coil compression spring 55, which, during the downward movement of the piston while the cradle is swinging rearwardly, is compressed.

As soon as the cradle has swung rearwardly to such extent as to release the bowling ball therefrom as shown in solid lines in Fig. 2, and after the ball has rolled out of the rear end of the cradle into the storage section, the compression of spring 55 urges the piston 36 upwardly. Upward movement of the piston 36 causes the oil above the piston to force the ball valve 52 downwardly and thereby fully releases ball valve 52 from its seat to permit oil or other liquid to more rapidly pass from above the piston through passageways 49, 50 and 51 to the space below the piston. This reverse swinging movement of the cradle will continue until the roller 27 strikes the stop plate 29, after which the cradle will be held in this position by spring 55 until another ball enters the cradle and strikes the roller 23.

It is believed the operation of this cradle safety ball stop will be understood from the above description. When the ball, rolling rearwardly along the ball return rack, enters the cradle, it will pass over roller 27 to clear the same and then strike the impact roller 23. The impact of the ball against roller 23 will be, to a large extent, absorbed by the hydraulic cylinder 33 and piston 36 therein, with a slight additional impetus being exerted against the cradle to complete its rearward swinging movement until the roller 23 is below the lowest surface of the ball in the rear trackway as shown in solid lines in Fig. 2. The ball will then roll rearwardly into the storage section.

Should a ball follow too closely after the first-mentioned ball, it will contact the roller 27 and be prevented from striking the ball within the cradle, which would otherwise probably cause injury to the bowler's fingers while handling balls in the storage section. This structure, just described, prevents such injury. When the cradle is in its ball-receiving position, as shown in Fig. 4, any ball in the storage section that may be pushed rearwardly by the bowler while hunting his own particular ball, would contact the cushion 31 on the rear face of the cradle and be there cushioned and prevented from entering the cradle and causing complications and possible injury by such entry.

The operation of this device may be better understood in Fig. 2 in which the ball 11', shown in dotted lines, has entered the cradle, which cradle at this time is in its ball-receiving position shown in dotted lines at 17. The cradle is then rotated rearwardly (in a clockwise direc-

tion as viewed in Fig. 2) until the impact roller 23 is below the ball return trackway, at which time the cradle and ball will be in the position shown in the solid lines in Fig. 2, with the ball leaving the cradle to pass into the storage section. At this same time the front roller 27 will be elevated sufficiently high to prevent a second ball 11'' following too closely after the first ball from entering the cradle until the cradle is again restored to its initial position as shown in Fig. 4, and in dotted lines in Fig. 2. With the cradle in the position shown in solid lines in Fig. 2, the second ball 11'' is stopped by the roller 27.

Also in Fig. 2 is shown in dotted lines how a ball 11b may be rolled rearwardly by the bowler while hunting his ball in the storage section, until it strikes the cushion 31 where it will be held and prevented from interfering with the further operation of the cradle. The various swinging positions of the cylinder 33 during the swinging operation of the cradle are shown in solid and dotted lines in Fig. 2, the piston rod being forced into the cylinder 33 when the cradle is in its ball-releasing position, and extending outwardly a distance from said cylinder when the cradle is in its ball-receiving position.

In the form shown in Figs. 8 and 9 I have provided a safety ball stop similar to that described above, except that the side walls 21' and 22' of the modified form, even though fixed to operate together, are laterally spaced apart a greater distance than in the preferred form, and the end wall 30 of the preferred form has been omitted.

In the modified form the cradle functions in the same general manner as that described above for the preferred form when a regular size bowling ball is used. However the distance between the side walls 21' and 22' and between the rollers 23' and 23'' (one on each side wall), while being small enough to retard a regular size bowling ball in the manner described above, is large enough that a ball of small diameter, such as a duck ball or the like, will pass right on through the ball stop when in the position shown in solid lines in Fig. 8. This is because a duck ball does not have finger holes and hence can be more easily picked up from the storage section by the player with less danger of injury to his fingers when a following ball comes right on through the ball stop. With duck balls the player does not have to move the balls backwardly hunting for his ball with his particular finger holes, hence he can grasp it on the sides without injury. In Figs. 8 and 9 the side walls each have a rear, outwardly extending flange a and b each having on its outer or rear face a cushion 31' similar in nature and operation to the cushion 31 of the preferred form.

I claim:

1. A safety ball stop for bowling balls, comprising, a ball return track, a stop frame fixed to said return track, a cradle swingably mounted on said frame and having when in ball receiving position a rearwardly and upwardly extending portion having a roller rotatably mounted in its upper end, said cradle when in ball receiving position having a forwardly extending portion with a roller rotatably mounted therein and positioned below the trackway of the return track, means operatively connected to the cradle for absorbing a large portion of the momentum of the ball when it enters the cradle and strikes the first mentioned roller, said cradle being reluctantly swingable in one direction to ball releasing posi-

tion by the remaining momentum of the ball to slowly release said ball, and means for swinging the cradle in the opposite direction for returning the cradle to ball receiving position when the ball has passed therethrough.

2. A safety ball stop as claimed in claim 1, in which the stop frame is provided with stop means against which the forward roller bears under the continued urging of said returning means when the cradle has been returned to ball receiving position.

3. A safety ball stop as claimed in claim 1, in which when the cradle is in ball receiving position the axis of rotation of the rear roller is above the horizontal plane passing through the center of the ball so that a ball striking said roller will be forced firmly against said track.

4. A safety ball stop for bowling balls, comprising, a ball return track, a cradle pivotally mounted with relation to the return track and having a rearwardly extending portion, and a forwardly extending portion, means resisting pivotal movement of the cradle when it is in ball receiving position, and a roller on the rearwardly extending portion, a roller on the forwardly extending portion, said rear roller being a substantial distance above the return track and above the center of a ball entering said cradle when the cradle is in ball receiving position, and the forward roller at that time being below the return track.

5. A safety ball stop as claimed in claim 4, in which when the cradle is in ball receiving position the axis of rotation of the rear roller is at a higher level than the horizontal plane passing through the center of the ball when the ball contacts the rear roller so that a ball striking said roller will be forced firmly against said track.

6. A safety ball stop as claimed in claim 4, having a stop frame to which the cradle is pivotally mounted, said frame having a stop member against which the front roller contacts when the cradle is in ball receiving position to hold the cradle in proper ball receiving position, a hydraulic cylinder pivoted to said frame, a piston in said cylinder, said piston having a piston rod pivoted to said cradle rearwardly of the axis of the cradle pivot.

7. A safety ball stop for bowling balls, comprising a ball return trackway, a stop frame fixed with relation to said trackway, a cradle swingably mounted on said frame and having a body portion extending rearwardly of the cradle fulcrum, said body portion also having a portion extending forwardly of the cradle fulcrum, a rotatable impact member in ball contacting position on the upper portion of the rearwardly extending portion of the cradle normally located above the center of a ball against which the adjacent portion of the ball continues to rotatably move after impact therewith said impact member serving to force the ball firmly against said trackway.

8. A safety ball stop as claimed in claim 4, having means for absorbing the greater amount of the momentum of a ball entering the cradle and permitting the ball to be gently released through the cradle as the cradle swings and means for automatically rotating the cradle in the opposite direction to return the cradle to ball-receiving position when the ball has been released therefrom.

9. A safety ball stop for bowling balls, comprising, a ball return trackway, a stop frame

fixed with relation to said trackway, said frame having laterally spaced apart side wall plates, a stop plate fixed in the upper forward portion of the frame between said plates, a cradle formed of laterally spaced apart side plates which are pivoted at an intermediate portion to said frame side wall plates, the front of the cradle contacting said stop plate when the cradle is in ball receiving position, the rear end of the cradle at this time extending upwardly and having an impact member mounted thereon with the center of the impact member at a higher level than the center of a ball in the cradle, means pivoted to the frame and to the cradle behind its pivot axis for absorbing momentum of a ball striking said impact member to gently release the ball from the cradle, and means for swinging the cradle to ball receiving position after a ball has been released therefrom.

10. A safety ball stop as claimed in claim 9, in which said impact member is a resilient roller.

11. A safety ball stop as claimed in claim 9, in which said impact member is a resilient roller said cradle having a transverse rear end wall, and a cushion member on the rear face of the rear end wall and located above the trackway when the cradle is in ball receiving position.

12. A safety ball stop as claimed in claim 4 wherein said rearwardly extending portion of the cradle is provided with a cushion member on the rear surface thereof, said cushion member being located above said track when the cradle is in ball-receiving position.

13. A safety ball stop for bowling balls comprising a frame member, a cradle pivotally mounted on said frame member and having a pair of laterally spaced side plates fixed to swing as a unit, said cradle being provided with means for receiving and absorbing the major portion of the impact of a regular bowling ball when the cradle is in ball-receiving position, said plates being spaced apart at the rear ends a distance sufficient to permit a small diameter ball such as a duck ball and the like to pass therethrough without contacting the cradle when the cradle is in ball-receiving position and spaced apart at the front ends a distance such that said small diameter ball will contact the cradle when a regular ball is in the cradle.

14. A safety ball stop for bowling balls, comprising, a frame member, a cradle pivotally mounted on said frame member, said cradle having a pair of laterally spaced plates the upper rear edges of which are formed on the front surfaces thereof with a curvature approximately corresponding with the curvature of a bowling ball, an impact roller rotatably mounted in the upper rear portion of the cradle between said plates, a roller rotatably mounted in the front end of the cradle between said plates, and means for resisting the rearward swinging of the cradle when a ball enters the cradle to slowly release a ball from the cradle, and means to return the cradle to ball receiving position when a ball has been released therefrom.

15. A ball stop for bowling balls comprising a cradle rotatably mounted adjacent a ball return track having, when in ball-receiving position, a rear portion extending above said track to a point above the center of a ball entering said cradle and a front portion beneath said track, means operatively connected to said cradle for absorbing a large portion of the momentum of a ball entering the cradle and striking said rear portion; said cradle being reluctantly rotatable to a

position where said rear portion is beneath the track to release the ball and the front portion is above the track to intercept a following ball, and means for rotating said cradle in the opposite direction to return said cradle to its initial position on passage of said first ball beyond the cradle.

16. A ball stop as claimed in claim 15 in which said rear portion is provided with a roller adapted to be contacted by said first ball and located above the center of a ball entering said cradle, and said front portion is provided with a roller adapted to be contacted by said following ball.

17. A ball stop as claimed in claim 15 in which there is provided a stop member against which

said forward portion is held by said return means when the cradle is in ball-receiving position.

ROBERT I. ANDERSON.
